Primary Examiner — Philip S Hyder*Assistant Examiner* — Roselynne Cody*(74) Attorney, Agent, or Firm* — Faegre Baker Daniels LLP(57) **CLAIM**

The ornamental design for a gas cap removal tool, as shown and described.

DESCRIPTION

FIG. 1 is a front elevational view of a gas cap removal tool showing my new design;

FIG. 2 is a rear elevational view thereof;

FIG. 3 is a view thereof showing the gas cap engaging end;

FIG. 4 is a view thereof showing the handle end;

FIG. 5 is a side elevational view thereof; and,

FIG. 6 is a side elevational view of the other side thereof. The broken lines in FIGS. 1 and 2 are directed to a portion of the gas cap removal tool that forms no part of the claim.
